UNITED STATES PATENT OFFICE.

CHARLES H. HOWARD, OF SAUGUS, MASSACHUSETTS, ASSIGNOR TO PAPER PRODUCTS MACHINE COMPANY, OF BOSTON, MASSACHUSETTS, A CORPORATION OF MASSACHUSETTS.

PAPER-REENFORCING MACHINE.

Application filed February 14, 1921. Serial No. 444,681.

To all whom it may concern:

Be it known that I, CHARLES H. HOWARD, a citizen of the United States, and residing at Saugus, county of Essex, and State of 5 Massachusetts, have invented an Improvement in Paper-reenforcing Machines, of which the following description, in connection with the accompanying drawings, is a specification, like characters on the drawings representing like parts.

This invention relates to machines for re-enforcing fabrics by filaments, and more particularly to machines for cutting and applying the cut filaments to a surface of the 15 fabric to be reenforced. The filaments to which reference is made may be of various kinds and may be either spun or unspun, but more particularly the present invention has reference to the application of cut un- 20 spun fibres to the fabric to be reenforced.

Attempts have heretofore been made to produce a reenforced paper by applying to the paper longitudinally thereof, a series of 25 parallel strands, strings or other spun reenforcing elements, and attempts have also been made to produce a reenforced paper by applying unspun fibres to a sticky surface of a paper web.

In making a satisfactory reenforced 30 paper, one of the greatest difficulties encountered is in securing reinforcement against longitudinal tear or rupture.

Reenforcement against tearing of the paper transversely is readily secured by applying to the paper, either spun or unspun reenforcing elements longitudinally of the paper, and while such reenforcement has advantages, it does not materially reenforce the paper against a longitudinal tear or 35 rupture. Attempts have also been made to solve this difficulty and strings or other form of spun fibres have been applied transversely of the paper web. The application of such transversely extending strings or 40 reenforcing elements, however, is costly and lacks economy of production.

An important feature of the present invention therefore consists in means for re-enforcing paper or other fabrics by cutting 45 filaments into lengths and adhesively applying the cut filaments to a surface of the paper or fabric with the cut filaments extending at random in various directions. A paper strip or fabric thus reenforced may 50 advantageously have applied thereto, a cov-

ering web to enclose the adhesive and the reenforcing filaments embedded therein between the two strips.

This feature of the invention may be satisfactorily carried out by feeding a relatively thin sheet of filaments from a source of supply to a cutter positioned adjacent the paper to be reenforced, and by operating the cutter to cut the filaments into lengths which are dropped or thrown in promiscuous order on to the adhesive surface of the paper strip or fabric. The sheet of filaments may be formed of either spun or unspun fibres but preferably the latter and such cut fibres will arrange themselves in various directions, some will extend transversely, others longitudinally, and others diagonally at various angles to the longitudinal direction of the strip to which they are applied. Thus the cut unspun fibres promiscuously applied to the paper or fabric, will impart increased strength to the same in all directions. To further increase the strength of the paper or fabric to resist longitudinal strains, the present invention further contemplates 70 means for adhesively securing to the paper strip or fabric, a layer of filaments preferably consisting of unspun fibres of long staple, longitudinally of the strip.

When unspun fibres are employed as the cut reenforcing filaments they may be conveniently supplied in the form of rovings or slivers, in which case means are provided for forming the rovings into a sheet, and for drawing out or attenuating the fibres as they are fed towards the fibre cutting means. This is desirable that the cut fibres may be distributed more or less uniformly over the paper or fabric to be reenforced. The longitudinally extending, reenforcing fibres may 80 likewise be supplied in the form of rovings and may be similarly converted into a relatively thin, substantially uniform sheet.

The accompanying drawings illustrate a good practical form of the invention, the details of which may be modified within the true scope thereof as defined by the claims.

In the drawings:

Fig. 1 is a side elevation, with parts in section of a machine embodying the present 105 invention;

Fig. 2 is a perspective view of features of the invention the view being taken from the far side of the machine shown in Fig. 1; and

Fig. 3 is an enlarged perspective view of 110

mechanism for applying cut fibres to the paper strip.

The machine illustrated is adapted to produce a two-ply reenforced strip of paper or fabric having the reenforcing filaments adhesively secured between the strips, but if desired, the upper strip may be omitted, as may also the longitudinally extending re-enforcing filaments.

- 10 Any suitable supporting frame may be provided, and in the embodiment shown, the frame consists of upright end posts 10 and 11 connected by horizontally-extending side bars 12. Between the spaced end posts 10 are mounted the paper or fabric supply rolls 13 and 14, the same being supported by suitable beams or spools 15 and 16. The strip of paper or fabric 17 is preferably led from its supply roll 13 over suitable guides 18 and 20 between a pair of rolls 19, 20. The roll 20 serves to apply an adhesive to one surface of the strip 17, and to this end the lower portion of the roll 20 rotates in an adhesive containing trough or box 21, so that as the strip 17 passes between the rolls 19 and 20 it will rotate the rolls and cause the lower roll to apply the adhesive in a well known manner. Any suitable adhesive may be used, but hot asphaltum is deemed preferable.
- 30 The strip 17 with the adhesive applied to its lower face may be led about the roll 22 suitably supported by the side bars 12, and then passes in the present instance of the invention, in an upwardly-inclined direction 35 toward a group of rolls supported by uprights 23 upon the machine frame. It is upon this inclined portion of the strip 17 that the cut fibres are applied, as will presently be described. After the reenforcing 40 filaments are applied, it is desirable that they be firmly embedded in the adhesive, and to this end the strip 17 with the fibres applied thereto passes between the rolls 24 and 25, rotatably supported by the uprights 23.
- 45 The strip passes substantially half-way around the roll 25 and then substantially half-way around the upper roll 26, in order that slipping between the rolls and paper will be prevented. The rolls 25 and 26 are 50 preferably adjustable vertically to vary the pressure between them by screw shafts or the like, operated by hand wheels 27 and 28. The reenforced strip may be led from the upper roll 26 to a takeup spool or beam 29, 55 rotated by suitable means (not shown).
- If the cut reenforcing filaments are unspun fibres, as is preferably the case, means is desirable for feeding the unspun fibres to the cutter, in the form of a comparatively 60 uniform sheet, that the cut fibres may be supplied in substantially the same quantity across the entire width of the paper strip or fabric. Satisfactory means to this end will now be described.
- 65 The unspun fibres may conveniently be

supplied in the form of rovings or slivers 30 drawn from cans or containers 31. Various types of unspun fibres may be used, but a relatively strong cheap fibre is preferable which is of sufficient length to be combed and attenuated into substantially parallel relation. The rovings 30 may be passed through openings in the table 32 and led along the upper face of the table between the rolls 33 to the fluted feed rolls 34, 35. The fluted rolls serve to draw the rovings forward and to flatten them out into a more or less uniform sheet as indicated by *a* (Fig. 3), but the rovings are flattened out to some extent by the rolls 33 before they reach the feed rolls as indicated by *b* (Fig. 3).

Between the fluted rolls 34, 35 and the fibre-cutting means is located means for drawing out and straightening the fibres. This means in the present instance of the invention consists of a series of traveling combs 36 suitably secured to sprocket chains 37 passing about sprocket wheels 38, 39 upon shafts 40, 41. The combs 36 are preferably moved at a higher speed than the speed at which the sheet of fibres are advanced by the fluted rolls 34, 35, and the upper run of the combs is positioned so that the comb teeth are drawn through the fibres. A bar 42 is preferably provided to 95 depress the sheet of fibres into engagement with the teeth of the combs, and the fibres pass from the combs to a pair of drawing rolls 43, 44. From the drawing rolls 43, 44 the fibres pass over a bar 45 where they are 100 cut by the rotating cutter 46. The drawing rolls 43, 44 are preferably rotated at a speed sufficiently high to draw the fibres forward at a speed in excess of the speed they are advanced by the combs 36, with the result that the fibres are drawn through the teeth of the combs and delivered to the cutter 46 in substantially parallel relation, and in a relatively uniform sheet. The cutter 46 may 105 consist of a roller having a cutter blade 47 secured thereto.

The fibre-feeding rolls and combs may be driven from any suitable means such as from a vertical shaft 48 extending downward from overhead driving mechanism and having a worm 49 meshing with a worm wheel 50 upon the shaft 40, and the fluted rolls 34, 35 are driven from the shaft 40, but at a slower speed by the chain 51 passing about sprocket wheels 52, 53 secured to the shaft 110 40 and roll 34 respectively. The paper feeding rolls, cutter and associated rolls may be driven by a belt 54 passing about a pulley 55 secured to the paper roll 26. A pulley 56 driven from the roll 26 by a belt 57 115 is secured to the lower fibre-feeding roll 44, and the upper roll 43 is driven from the roll 44 by gears 58, 59, while the cutter 46 is driven by gears 60, 61 (Fig. 2).

The rotating cutter 46 and cooperating 120

bar 45, in the embodiment shown, are positioned above the upwardly inclined portion above mentioned, of the strip 17, so that as the fibres are cut they are pushed or kicked off the bar 45 by the rotating cutter, and fall promiscuously upon the inclined portion of the strip as indicated at *c*. The cut fibres *c* thus applied to the strip 17 will extend at random in various directions as clearly shown in Fig. 3. The length of the cut fibres *c* will depend upon the speed at which the cutter is driven relative to the feed rolls 43, 44, and this may be varied as desired, by changing the gears 60, 61. The speed at which the paper strip *c* is advanced preferably is such that the cut fibres are deposited upon the paper in a thin layer having a thickness substantially corresponding to the thickness of the individual fibres.

As above stated, it may be desirable to further reenforce the paper strip or fabric 17 by applying thereto longitudinally-extending filaments *d*. Mechanism for applying such fibres under lengthwise tension will now be described. The longitudinal reenforcing fibres *d* may be combed and attenuated by mechanism substantially similar to the mechanism described for combing and attenuating the cut fibres *c*, and one set of attenuating mechanism may conveniently be positioned above the other as clearly shown in Fig. 1. The mechanism for applying the fibres *d* to the strip 17 under lengthwise tension is here shown as similar to the mechanism described and claimed in the Howard and Sharp application, Serial Number 391,433, filed June 24, 1920.

The unspun fibres *d* are conveniently supplied in the form of rovings 62 drawn from containers 63 through openings in a table 64 and are drawn along this table between the rolls 65, 66 and between the fluted feed rolls 67, 68. The rovings 62 leave the fluted rolls in substantially sheet form, and may then be led upward over a spreader bar 69, down under a depresser bar 70 and to the traveling combs 71 secured to sprocket chains and operated similar to the combs 36. The fibres *d* after being combed and straightened by the mechanism just mentioned, is led along a guide plate 72 and is delivered to the nip of the rolls 24 and 25 where it is applied to the adhesive surface of the strip 17. The strip 17 is preferably advanced at a speed considerably in excess of the speed of the combs 71 so that as the leading ends of the fibres *d* are applied to the strip, the trailing portions of the fibres are drawn forward through the teeth of the combs. This attenuates the sheet of fibres and causes them to be tensioned lengthwise as they are applied to the strip.

The combs 71 may be operated from the vertical shaft 48 by a worm 73 meshing with the worm wheel 74, and the fluted rolls

67, 68, may be driven by the sprocket chain 75 similar to the drive of the fluted rolls 34, 35. The fluted roll 67 may be adjusted relative to the roll 68 by suitable adjusting means operated by the hand wheel 76, and provision may also be made for relatively adjusting the fluted rolls 34, 35.

Should it be desired to apply a strip of paper or fabric over the reenforcing filaments upon the strip 17, this may be readily accomplished by leading the strip 77 from the supply roll 14 over the guide roll 78. The strip 77 is then led to the nipple of the rolls 24, 25 when it is applied to the adhesive surface of the strip 17, and the two-ply reenforced strip 79 passes from the upper roll 26 to the takeup roll 29.

From the foregoing description, when read in connection with the drawings, it will be seen that paper strip or fabric may be rapidly and inexpensively reenforced both longitudinally and transversely by the machine herein disclosed.

What is claimed is:

1. In a machine for reenforcing paper, the combination of means for applying adhesive to the surface of a paper strip to be reenforced, means for cutting unspun fibres into lengths and promiscuously applying the cut fibres to the adhesive surface of the paper strip, means for applying unspun fibres longitudinally of the paper strip, and means for forcing the cut fibres and longitudinal fibres into intimate engagement with the adhesive.

2. In a machine for reenforcing paper, the combination of means for applying adhesive to the surface of a paper strip to be reenforced, means for cutting filaments into lengths and promiscuously applying the cut filaments to the adhesive surface of the paper strip, means for applying filaments longitudinally of the paper strip and under lengthwise tension, and means for forcing the cut filaments and tensioned filaments into intimate engagement with the adhesive surface of the paper.

3. In a machine for reenforcing paper, the combination of means for feeding paper strips to be reenforced and applying one strip to the other, means for applying adhesive to the inner surface of one of the paper strips, means for cutting filaments and promiscuously applying the cut filaments between the paper strips and means for applying filaments longitudinally of the paper strips.

4. In a machine of the character described, the combination of means for feeding a fabric to be reenforced, means for feeding two sheets of unspun fibres towards the fabric, means for attenuating the unspun fibres of each sheet, means for cutting the attenuated fibres of one sheet into lengths and adhesively applying them to a

4

surface of the fabric with the cut fibres extending at random in different directions, and means for adhesively applying the attenuated fibres of the other sheet to the 5 fabric.

5. In a machine of the character described the combination of means for feeding a fabric to be reenforced, means for feeding two sheets of filaments towards the 10 fabric, means for cutting the filaments of one sheet and adhesively applying the cut filaments to a surface of the fabric with the cut filaments extending in different directions, and means for adhesively applying 15 the filaments of the other sheet to the surface of the fabric.

6. In a machine for reenforcing a paper strip by the application of cut reenforcing filaments thereto, the combination of paper 20 feeding means for feeding a strip of paper having an exposed adhesive surface, means for applying reenforcing filaments to the adhesive surface of the paper strip in longitudinal relation thereto, mechanism for 25 feeding a sheet of reenforcing filaments towards the adhesive surface of the paper, a cutter adjacent the exposed adhesive surface of the paper for cutting the sheet of filaments into lengths as it approaches the adhesive surface of the paper and applying 30 the cut filaments directly thereto.

7. A machine for reenforcing paper, comprising in combination, means for feeding a paper strip having adhesive applied to one 35 face thereof, means for feeding toward the paper strip a sheet of relatively long unspun fibres having the individual fibres arranged in substantially parallel relation, a cutter having a blade extending trans- 40 versely of the sheet of fibres to cut the sheet

at equal intervals into short straight fibres of approximately uniform length, and said cutter being adapted to throw the fibres as they are cut directly on the adhesive face of the paper so that the individual fibres upon 45 striking the paper will fall at random in all directions to reenforce the paper.

8. A machine for reenforcing paper, comprising in combination, means for feeding a paper strip having adhesive applied to a 50 face thereof, means for feeding a sheet of relatively straight and parallel unspun fibres toward the paper to be reenforced, a cutter for severing the sheet of fibres at equal intervals to cut the fibres into short 55 straight lengths and free them from the source of supply so that the fibres are applied directly to the paper as they are cut with the individual fibres extending promiscuously in all directions to reinforce the 60 paper, and means for forcing the cut fibres into the adhesive of the paper strip.

9. A machine for reenforcing paper, comprising in combination, means for feeding a paper strip having adhesive applied to a 65 face thereof, means for feeding toward the paper strip a sheet of filaments having the individual filaments disposed in a comparatively straight parallel condition, a cutter extending transversely of the sheet of filaments to sever the sheet at equal intervals 70 into short straight filaments of approximately uniform length for application directly upon the adhesive face of the paper with the individual cut filaments extending 75 promiscuously in all directions to reinforce the paper.

In testimony whereof, I have signed my name to this specification.

CHARLES H. HOWARD.
